UNITED STATES PATENT OFFICE

119,522

DESIGN FOR A REAMER FOR SMOKING PIPES

Julius Kohn, New York, N. Y.

Application November 22, 1939, Serial No. 88,425

Term of patent 3½ years

To all whom it may concern:

Be it known that I, Julius Kohn, a citizen of the United States, residing in the city of New York, county of Bronx, State of New York, have invented a new, original, and ornamental Design for a Reamer for Smoking Pipes, of which the following is a specification, reference being had to the accompanying drawing, forming part thereof.

In the drawing:

Figure 1 is a front elevation of a reamer for smoking pipes, showing my new design.

Figure 2 is a rear elevation thereof.

Figure 3 is an edge elevation, and

Figure 4 is an end view of the blade end of the reamer.

What is claimed is:

The ornamental design for a reamer for smoking pipes, as shown.

JULIUS KOHN.
